UNITED STATES PATENT OFFICE.

WILLARD C. JAMES, OF LOS ANGELES, CALIFORNIA.

SEATING TABLE.

Application filed August 30, 1926. Serial No. 132,474.

An object of this invention is to provide a compact unitary article of furniture comprising a table and seats for seating persons around the table; and adapted to fold into the space of and to serve as a table alone.

An object is to economize space commonly necessary to accommodate seats for those sitting about the table.

The invention is adapted for many uses, and in various situations and is broadly new basic and pioneer in numerous respects in that it has, hinged to its legs, seats adapted to fold flatwise against such legs; and the seats are provided with seat supporting legs hinged thereto and adapted to fold against the seats when the seats are folded against the table legs, thus making a compact article of furniture; provision is also made whereby the seats may be constructed in hinged sections so as to fold against the table legs beneath both the side and the end edges of the table top; and provision is also made for folding end seats under the table top and within the frame of the table, for providing strong seat sections, and for minimizing exposure of the seat hinges.

A feature of the invention is the construction of the seat legs of flat material of considerable width compared to the thickness of the legs so that they fold into comparatively small space.

Other objects, advantages and features of invention may appear from the accompanying drawings, the subjoined detailed description and the appended claims.

The accompanying drawings illustrate the invention in the form at present deemed most desirable.

Figure 1 is a broken perspective view of a table constructed in accordance with this invention, partly folded and partly unfolded. Some parts are broken away to expose parts otherwise hidden.

Fig. 2 is a plan of the table partly folded and partly unfolded; the table top and leaves being omitted and outlined in broken lines; one end seat and one side seat are shown extended and the other seats are shown folded.

Fig. 3 is an end elevation of the table folded. Broken lines indicate the side seats extended. The leaf is raised to expose the end construction.

Fig. 4 is a side elevation of the table folded; broken lines show one end seat and one end leaf extended.

Fig. 5 is a fragmental detail illustrating

the seat, end extension and hinge mounting; line $\alpha\beta$, Fig. 6 indicates the plane of section, the seat being folded up against the table leg and end frame pieces, a fragment of one of which end pieces is shown in horizontal section.

Fig. 6 is a fragmental detail looking at the left end of the main seat section and the bottom side of the left end seat extension as the same appears when folded against the table leg 1 shown at the left in Fig. 1.

Fig. 7 is a section between the hinges at the right end of the seat shown at the front in Fig. 1; the main seat section and the right end seat section are shown folded against a table leg.

The table legs 1 may be of any suitable size and form and the upper portions thereof are shown rectangular in cross section. The side frame pieces 2 are secured by any suitable means as by screws a to the inner sides of the legs; and the end frame pieces 3 are in like manner secured by screws a' to the outside of the legs. The top edges of the frame pieces are flush with the top ends of the table legs to form a firm true surface onto which the table top 5 is secured in any suitable well known way as by screws b .

The lower edges of the side frame pieces 2 are recessed to provide accommodating spaces 6 for the legs of the occupants of the main side seat members 7, 7', that are hinged at their inner ends by hinges 8, mounted on projecting blocks 12 that are fixed to the outer sides of the table legs about half way between the top and bottom ends of such legs; and the inner edges of the main seat sections 7, 7', are recessed as at 9 to cooperate with recesses 6 of the side frame pieces 2, to accommodate the legs of persons seated on such main seat sections.

The main seat sections are provided at their mid-lengths with broad flat seat supporting legs 10 hinged to the under sides of said sections by leg hinges 11, to fold toward the inner or hinged edges 13 of the main seat members. The hinges 8 are shown with projecting knuckles 14; and when desired, the main seat members may be folded flatwise against the outer faces of the table legs, with the outer edges of said members against or close to the underside of the table top. The blocks 13 serve the double purpose of spacing the seats 7 and 7', when in extended positions for use, laterally from the table, for greater comfort to the occupants and serve

as supports for the seats, their extensions and supporting legs, when in folded positions to thereby relieve the hinges 12.

The main seat sections are respectively 5 provided with folding end extensions 15, 15' hinged thereto by hinges 16; and the seat extensions 15 are adapted to be folded against the table legs. The weight of the folded seat extensions tends to hold the folded main seat, 10 upright, edgewise, and flatwise against the sides of the table legs.

The main seat sections are shown provided on their under sides with end cleats *c* to strengthen such sections, and the main seat 15 hinges 8 are seated on said cleats.

The end seat extensions 15, 15', are joined by a miter joint to the main seat members 7, 7', and are hinged by hinges 16 let into the mitered ends of said extension and sections 20 so that the seat extensions of each seat section may be folded flat against the top faces of such section, or may project at right angles to such section, to fit snugly against the end faces of the table legs.

25 Each seat extension is provided near its middle with a transverse flat seat extension leg as at 17, 17', hinged by one or more hinges as at 18, 18', to fold toward the free end of such extension.

30 The side seat sections as at 7 are longer than the spaces between the end faces 19 of the table legs, to form projecting abutments 20 and 20' when the sections 7 and 7' are folded up against the legs. Such abutments 35 are of different lengths, one as at 20, being about equal in length to the thickness of the seat extensions 15, 15', so that when the seats are folded up and the extensions are folded toward the faces of the table legs, the seat extension 15 on one side of the table will fold over onto and lie flat against the end extension 15' of the seat on the other side of the table.

35 The seat extensions 15' are provided with 45 seats formed by blocks 21 on which one leaf of each leg hinge 18, 18' is fixed, so that when the extensions 15' are folded against the end faces of the table legs and the extensions 15 are folded onto the extensions 15', the legs 50 17' may fold over the extensions 15, and the legs 17 may fold over the extensions 15'. The legs 17 and 17' are of the same thickness and are arranged on their seat sections so that they fold edge to edge, and their outer 55 faces are flush with each other.

The ends of the table top project to form abutments 22 to which leaves 23 are hinged as at 24. Said abutments overhang the folded end sections and legs, and when the 60 leaves are let down, they fold against the seat section leaves, as shown in Fig. 4.

The legs at one end of the table are provided with rubber tired wheels 25 on an axle 25' and the legs at the other end of the table 65 are provided with casters 26; the wheels be-

ing mounted on the ends of said axle 25' that extend beyond the table legs, and the table may be moved over a bare or carpeted floor with great ease and facility in every direction when the seat legs are off the floor; but 70 when such legs are on the floor, the table is held stationary by the friction of the seat legs on the floor.

75 End seats 27 are provided with swinging legs 28 that are adapted to rest on the floor when the seats are to be occupied and said seats are connected to the legs of the table by a jointed connection formed of a link 29 journalled to the end seat at one end and two links 30 pivoted to link 29 by a pivot 31 and pivoted to the table legs as by the coaxial pivots 32; the link 29 being free to swing between the two links 30, to allow the end seat 27 to be swung from its extended position shown at the right end of Fig. 1 to the retracted position shown at the left end of Fig. 1, and at the right end of Fig. 2.

80 Supporting pins 33 project inwardly from the side rails 2 of the table to receive the end seat 27 between the pins and the table top; and the end seats have transverse slots 34 to hook onto a flanged catch 35 that is fixed to a pin 36 projecting inwardly from the end rail 3 of the table frame, there being an end seat 85 and catches and pins therefor at each end of the table.

85 The end leaves 23 of the table are shown provided with a shoulder 37 to rest on the end of a prop 38 pivoted to the table end 3 by the joint 39 and adapted to be moved into and out of propping position as required to hold the table leaves up or to allow them to be lowered.

90 The joined edges of the main seat sections 7 and 7' and their end extensions 15 and 15' are beveled at an angle of 45 degrees and the leaves of the hinges 16 are fitted to the level faces as at 40 and the knuckles of the hinges are uppermost when the seat is down so that the joints are rigid against depression of the 95 end extensions and the seat board formed by the parts 7, 15 and 15' is rigid with respect to depression of the end extensions when the main section is supported by its leg 10, and the legs 17 and 17' are shown hinged to the 100 undersides of such extensions centrally between the joint at 40 and to the ends of the extensions so that the weight of one seated on the extension will be carried by the leg without danger of breaking the joint. The 105 miter joint also affords a wider face to receive the leaves of the hinges so that wider hinge leaves can be used than would otherwise be practical.

110 Reinforcement for the miter joints 40 are provided in the form of dowels 41 embedded longitudinally in said joints, being glued in the beveled ends of the main side seat members 7 and 7' and fitting in cavities 42 in the bevel edges 40 of the seat sections 15, 15'. 115

I claim:—

1. In combination with table legs; a main seat hinged to such legs on one side of the table; means to support the main seat in seat-
5 ing position; a seat section hinged to the end of the main seat and adapted to be made to extend across the end of the table and below the table top when the main seat is folded up at the side of the table, the pins of the hinges
10 between the main seat and the seat section being arranged at the upper sides of the seat section, so that the weight of the end sections will hold the main seat in folded position at the side of the table when the seat section is
15 folded against the table legs at the end of the table.

2. In combination with a table, having legs, a seat proper hinged to the table legs for folding vertically thereagainst when not
20 in use, a seat extension hinged to the seat proper and folded vertically therewith and

substantially at a right angle thereto, whereby the weight of the seat extension will tend to hold the seat proper in folded position.

3. In combination with a table having 25 legs, a seat proper having its inner edge hinged to the legs at one side of the table to fold upwardly and to stand vertically thereagainst, a folding support for the seat when in position for use, a seat extension having 30 one of its ends hinged to an end of the seat proper to fold upwardly with the seat proper, and stand vertically against the legs at an end of the table and at substantially a right angle to the seat proper, whereby its weight 35 will counterbalance the seat proper and thus hold it with its folding support in folded position.

In testimony whereof, I have hereunto set my hand at Los Angeles, California, this 40
23rd day of August, 1926.

WILLARD C. JAMES.
